[57] CLAIM

The ornamental design for scaper for removing paint, as shown and described.

DESCRIPTION

FIG. 1 is a front perspective view of a scaper for removing paint, showing my new design;

FIG. 2 is a rear perspective view thereof;

FIG. 3 is a side elevational view, the opposite side being a mirror image thereof;

FIG. 4 is a top view thereof, taken in the direction of arrow 4 of FIG. 3;

FIG. 5 is a side elevational view of the scaper with the head attached in an alternate way;

FIG. 6 is a front elevational view of the scaper as shown in FIGS. 1-3;

FIG. 7 is a rear elevational view thereof.

FIG. 1

FIG. 2

FIG. 3

FIG. 5

FIG. 4

FIG. 6

FIG. 7
